EDWARD F. WRENCH, OF HARTWICK, NEW YORK, ASSIGNOR TO
BERNARD L. WRENCH, OF WHITESBORO, NEW YORK.

POLE-AND-YOKE CONNECTION.

No. 826,005.

Specification of Letters Patent.

Patented July 17, 1906.

Application filed March 13, 1905. Serial No. 249,788.

To all whom it may concern:

Be it known that I, EDWARD F. WRENCH, a citizen of the United States, residing at Hartwick, in the county of Otsego and State 5 of New York, have invented certain new and useful Improvements in Pole-and-Yoke Connections, of which the following is a specification, reference being had therein to the accompanying drawings.

10 My invention relates to an improved pole-and-yoke connection for wagons; and I declare that the following is a full, clear, concise, and exact description thereof sufficient to enable one skilled in the art to make and 15 use the same, reference being had to the accompanying drawings, in which like letters refer to like parts throughout.

The purpose of my invention is to produce 20 a cheap and efficient means of fastening the pole of a wagon to the neck-yoke by parts which are simple in their construction and yet easily connected and at the same time safe and convenient. The invention is disclosed in one form in the following specification and in the drawings therein referred to, and in which—

25 Figure 1 is a side view showing the pole-head, the yoke with its band, and link connections. Fig. 2 is a front view of the pole-head. Fig. 3 is a top view, and Fig. 4 is a bottom view, of the same. Fig. 5 is a bottom view of the yoke-band and link connection; and Fig. 6 is a view of the link connection inverted. Fig. 7 is a partial view in section, showing 35 the manner of connecting the pole and the yoke members.

Referring to the figures more in detail, A represents the pole-head proper, which has upper band *a* and lower band *a'* for mounting 40 the same on the wagon-pole by means of bolts *a''*. In the construction which I prefer this member is made up of separate castings, the part A and *a* and the part A' and *a'* being integral, the two being held together by bolt B; but the entire pole-head member may be 45 made integral, depending upon the skill of the mechanic. The parts A and A' when together form a head which is substantially hollow, having an opening C in the lower and front part, the lower end of which is flared outwardly, as shown at *c*.

D is the yoke-band encircling the yoke *d* and secured at the ends by bolts *d'*, passing through the yoke-band and the link E, which

is flared at its upper end where the ends of the 55 yoke-collar D are brought against it and is there provided with openings for bolt *d'*. The form and arrangement of these parts is adapted to permit the yoke-band to be spread so as to receive a larger yoke and still bear 60 against the sides of the link. The holes in the link are elongated or are made in the form of slots *d''*, Fig. 5, to permit of such an adjustment. Depending from link E is link 65 bar or arm F, which has at one end a broadened head *f*, substantially as shown, which extends from one side of link-bar F and is recessed, as at *f'*. This link-bar is passed freely in the opening C, the head *f* slipping easily through the enlargement *e*, as in position *x*, Fig. 7. The link-bar F is then turned 70 downwardly and then pushed up and its head passed behind the bolt B, as indicated in position *y* in Fig. 7. After this it is brought to the position shown at *z* in that figure, when 75 the connection between the pole-head and the yoke is complete, as seen in Fig. 1.

I illustrate my invention in a single construction; but various modifications can be employed without departing from the invention. If the pole-head, for instance, is made 80 in a single piece, it can be provided with an integral member to take the place and perform the function of the bolt B in the drawings. I do not, therefore, limit myself to the 85 particulars illustrated.

Having described my invention, what I claim as new, and desire to secure by Letters Patent, is—

1. In a device of the character described, a 90 pole-head member, a yoke member and a link connection therebetween comprising a flaring-headed link-arm, the pole-head being cut out to receive the link-arm in a vertical position from below and lock the same therein 95 when in a horizontal position, in combination, substantially as described.

2. In a device of the character described, a pole-head member and a yoke member, in combination with a link-headed member supported on the yoke member and adapted to be inserted and hooked into the pole member and swung therein between the forwardly-extending parts of the pole-head, substantially 100 as described.

3. In a device of the character described, a 105 pole member longitudinally recessed and having an opening on the under and forward sur-

2
face thereof flared at one end, a headed hook-like member adapted to fit into the said opening, means in the pole member to engage the said hook, the said hook being supported at its other end on the yoke member, substantially as shown.

4. In a device of the character described, a longitudinally - recessed pole member provided with transverse bolt therein, a headed hook member adapted to engage the said bolt and to be slipped into such position from the under side of the pole member and be held rigid by the latter thereby supporting the pole on the hook member by engagement of the hook with the bolt, in combination, substantially as described.

5. A device of the character described comprising a pole member and a yoke-engaging member with a link member and a hook member adapted to connect the two, the said

link member being flared at one end to engage the ends of the yoke-engaging member so as to permit the same to be adjusted to different sizes of yokes and to retain a close bearing on the yoke member, substantially 25 as described.

6. In a device of the character described, a hollow pole-head with a cross-bolt therein, a hook member to engage said bolt and be held in the pole-head thereby and extend forwardly, and the pole-head being formed to engage the hook and prevent upward and side movement, substantially as shown.

In testimony whereof I affix my signature in presence of two witnesses.

EDWARD F. WRENCH.
